Primary Examiner — John A Voytek(74) *Attorney, Agent, or Firm* — RatnerPrestia(57) **CLAIM**

The ornamental design for an aircraft, as shown and described.

DESCRIPTION

FIG. 1 is a front perspective view of an aircraft; FIG. 2 is a rear perspective view thereof; FIG. 3 is a front elevation view thereof; FIG. 4 is a rear elevation view thereof; FIG. 5 is a left side perspective view thereof, the right side view being a mirror image thereof; FIG. 6 is a top plan view thereof; and, FIG. 7 is a bottom plan view thereof.

In the drawings, the dashed broken lines depict portions of the aircraft that form no part of the claimed design. The dot-dash broken lines define the bounds of the claimed design and form no part thereof.

1 Claim, 7 Drawing Sheets(56)
